H. G. Burns, Attorney.

UNITED STATES PATENT OFFICE.

ANTHONY C. MANNWEILER, OF FORT WAYNE, INDIANA.

DESIGN FOR AN INCANDESCENT ELECTRIC LAMP.

59,500.

Specification for Design.

Patented Oct. 25, 1921.

Application filed June 9, 1921. Serial No. 476,354. Term of patent 14 years.

To all whom it may concern:

Be it known that I, ANTHONY C. MANNWEILER, a citizen of the United States, residing at Fort Wayne, in the county of Allen and State of Indiana, have invented a new, original, and ornamental Design for an Incandescent Electric Lamp, of which the following is a specification, reference being had to the accompanying drawing, forming part thereof.

Figure 1 is an elevation of an incandescent electric lamp showing my new design; and Fig. 2 is a plan view projected from Fig. 1.

I claim:

The ornamental design for an incandescent electric lamp, as shown.

ANTHONY C. MANNWEILER.
